COIL HOLDER

John C. Holdgate and William P. Donald, Warren,
Ohio, assignors to The Wean Engineering Com-
pany, Inc., Warren, Ohio, a corporation of
Ohio

Application January 18, 1941, Serial No. 375,084

13 Claims. (Cl. 242—72)

This invention relates to a coil holder for supporting a coil of metal strip and, particularly, to an uncoiler, although the fundamental principles of the invention will apply to a coil holder in general.

In the operation of continuous strip mills, the present trend is toward the handling of larger and larger coils, because this effects an economy of time by reducing the frequency of threading a new coil through the mill. It is common, for example, to build up coils as large as 60" in outside diameter, with a 20" eye or inside diameter, weighing 700 pounds per inch of width. The problem of supporting a coil of this size, while being unwound for processing in strand form, is rendered more difficult by the relatively small size of the eye, which limits the size of the mandrel of the coil holder. The great weight involved by the large outside diameter of the coil introduces further difficulties. A portion of the diameter of the eye, furthermore, must be allowed for the expansion of the mandrel. The factors already mentioned, however, place a strict limit on the amount of space available for expansion. If only a limited amount of expansion of the mandrel is possible, the coil holder cannot support coils whose inside diameter may vary materially. For obvious reasons, the amount of mandrel expansion should be as great as possible.

We have invented a novel coil holder having an expanding mandrel which is sufficiently strong to support the large coils now favored by steel mill operators and, at the same time, has a comparatively large degree of expansion and a small over-all diameter when collapsed. In a preferred embodiment of the invention, we provide a rotatable mandrel with radially movable segments and mount a wedging member for longitudinal movement relative to the mandrel. This member and the segments have cooperating inclined surfaces to effect initial expansion. We also provide further means, in the form of links connecting the segments and the wedging member, adapted to cause continued expansion after the inclined surfaces have produced the maximum expansion of which they are capable. We thus gain the advantage of positive operation characteristic of mandrels contracted and expanded by link members only, and a greater range of expansion than is obtained by the use either of wedges or of links alone. A further advantage is that the pivoted links exert a positive collapsing movement of the segments on retraction of the wedging member.

Further details and advantages of the invention will be pointed out in the following complete description and explanation with reference to the accompanying drawings illustrating the 5 aforementioned preferred embodiment. In the drawings:

Figure 1 is a view partly in elevation and partly in section along a vertical plane through the axis of the mandrel of our coil holder;

10 Figure 2 is a sectional view taken substantially along the plane of line II—II of Figure 1, showing parts in elevation;

Figure 3 is a transverse sectional view through the mandrel, taken substantially along the plane 15 of line III—III of Figure 1; and

Figure 4 is a view partly in section along the plane of Figure 1 and partly in end elevation.

Referring now in detail to the drawings, the coil holder of our invention indicated generally 20 at 10 comprises a mandrel 11 having a journal portion 12 extending from one end thereof and rotatably mounted in bearings 13 seated in a housing 14. The housing has a base portion 15 adjustable along ways 16 on a bed plate 17. A gear 18 is keyed to the journal portion 12 of the mandrel 11 and meshes with a pinion 19 on a shaft 20, also journaled in bearings mounted in housing 14. The shaft 20 is connected by a coupling 21 to the shaft of a gear motor 22. By 25 this means, the mandrel 11 may be rotated at the proper speed to deliver strip in strand form from a coil thereon indicated at 23, to a processing line, e. g., a shearing line, pickling line, or the like.

30 The mandrel 11 is slotted longitudinally to receive segments 24, spaced circumferentially thereof. The segments have body portions 25 fitting within the recesses in the mandrel and shoe portions 26 exposed on the exterior thereof.

35 The segments are radially movable by means about to be described from the positions shown in solid lines in Figure 3 to the positions shown in dotted lines, and vice versa. On expansion, the segments grip the interior of the eye of a 40 coil previously disposed on the mandrel.

An expander or wedging member 27 is movable 45 longitudinally in a central bore in the mandrel 11. The expander 27 is carried in a shaft 28, one end of which extends through the journal 50 portion 12 of the mandrel and outwardly beyond the bearing 13 remote from the mandrel, through a packing gland 29. The shaft 28 is slideable in bushings 28' carried by the mandrel. The shaft 28 has a shoulder 30 bearing against the inner 55 end of the expander 27, and is pinned to the

latter adjacent the other end, as at 31. The mandrel 11 has a removable cap 32 to permit insertion of the expander 27.

The expander 27 has inclined surfaces 33 intermediate the ends thereof, adapted to cooperate with similar surfaces 34 on the body portion 25 of the segments 24. By this construction, movement of the expander 27 toward the right, as viewed in Figure 1, relative to the mandrel 11, will cause outward radial movement or expansion of the segments 24.

Links 35 are pivoted to the segments 24 adjacent to each end thereof and to the expander 27. The expander has slots 36 to receive pins 37, securing the links 35 thereto, whereby the initial longitudinal movement of the expander does not cause any movement of the pins 37. In other words, the slots 36 provide a lost-motion connection. Pins 37 secure the links to the segments 24.

We provide power means for actuating the shaft 28 longitudinally to move the expander 27 outwardly and inwardly relative to the mandrel 11. This means may conveniently take the form of a fluid-pressure cylinder 38 mounted on the base portion 15 of the housing 14 having a piston 39 therein and a piston rod 40. The piston rod 40 is connected to the shaft 28 through a thrust bearing 41, the outer race of which is secured in a cup 42 threaded onto the piston rod. The inner race of the bearing is secured on the end of the shaft 28 by a nut 43. Connections 44 to opposite ends of the cylinder 38 and a suitable control valve (not shown), permit operating fluid to be admitted to the cylinder to actuate the shaft 28 outwardly or to the right, as viewed in Figure 1, and then to retract it.

It will be apparent that the initial outward movement of the expander 27, as previously stated, forces the segments outwardly, by reason of the cooperation between the inclined surfaces 33 and 34. This tilts the links 35 slightly. The slope of these surfaces, however, must be small in order to provide the necessary mechanical advantage. This means that the total expansion which can be produced thereby is relatively small. After a predetermined movement of the expander 27, however, the ends of the slots 36 therein engage the pins 37. Thereafter, continued movement of the expander 27 causes further angular movement of the links 35. Since the segments 24 are confined against longitudinal movement, the continued angular movement of the links 35 causes further outward movement of the segments and separation of the surfaces 33 and 34.

By this mechanism, the shoes 26 of the segments 24 are caused to engage the interior of the eye of a coil with sufficient force to maintain it against slippage and in truly cylindrical form as it is being uncoiled.

When it is necessary to remove the coil from the mandrel before it is completely unwound, or when the uncoiling has been completed, the shaft 28 and expander 27 are actuated to the left, as viewed in Figure 1. When the ends of the slots 36 engage the pins 37, the segments are positively pulled inwardly or contracted.

The coil holder described is particularly useful in connection with a car 45 traveling on rails 46 and having a coil-supporting platform 47 tiltably mounted thereon. The platform is carried on a liftable standard 48 slidable in a well 49 depending from the car frame. The car is more fully described and claimed in the copending applica-

tion of Klaus Egge, Ser. No. 392,093, filed May 6, 1941, for Apparatus for handling coils.

It will be apparent from the foregoing description that the invention is characterized by numerous advantages. The combination of the wedging member and pivoted links for expanding segments provides a greater range of expansion than would be possible with either expanding means alone. By the construction shown, a large expansion is possible, without requiring a minimum over-all diameter of the mandrel exceeding the size of the eye in even the largest coils. The construction is also such as to provide ample strength for supporting the heavy coils now being rolled.

The weight of the coil is transferred through the segments, wedging member, shaft, and bearings 28', directly to the mandrel, so that the shaft itself is not subjected to any substantial bending moment. This makes it possible to use a small shaft to provide space necessary for the wedge and linkage mechanism.

The invention overcomes the limitations of an expanding mandrel actuated solely by wedges or links. In either case, the amount of expansion obtainable is relatively slight, particularly where the maximum diameter available is small, compared to that characterizing our invention. The positive collapsing of the segments is a great advantage over conventional wedge type expanding mandrels, which are sometimes very difficult to collapse. Similarly, the expanding action is positive throughout the range, as compared to the use of links alone, because with the latter, expansion is positive only near the limit of outward movement. At intermediate points, there is not sufficient mechanical advantage with links alone to obtain effective gripping of the coil. With our construction, the wedging surfaces provide the expanding force until the links are in position to operate effectively in continuing the expansion.

Although we have illustrated and described but a preferred embodiment of the invention, it will be recognized that changes in the construction and arrangement disclosed may be made without departing from the spirit of the invention or the scope of the appended claims.

We claim:

1. In a coil holder, a mandrel, means supporting said mandrel for rotation, segments movable radially in said mandrel, a member movable axially of the mandrel, said member and segments having cooperating wedging surfaces whereby axial movement of the member effects an initial outward movement of said segments, and links pivoted to said member and said segments adapted to cause further outward movement and separation of said surfaces on continued axial movement of said member, said links having a lost-motion connection with said member.

2. In a coil holder, a mandrel, means supporting said mandrel for rotation, segments movable radially in said mandrel, a member movable axially of the mandrel, said member and segments having cooperating wedging surfaces whereby axial movement of the member effects an initial outward movement of said segments, and links pivoted to said member and said segments with a lost motion connection whereby they are effective on continued movement of said member to cause further radial movement of the segments.

3. In a coil holder, a mandrel, means supporting said mandrel for rotation, segments movable

radially in said mandrel, a member movable axially of the mandrel, said member and segments having cooperating wedging surfaces and expanding links effective successively on axial movement of said member to cause continued outward movement of the segments, said links having a lost-motion connection with said member.

4. In a coil holder, a rotatable mandrel, coil-engaging segments movable radially in the mandrel, a wedging member movable axially in the mandrel and effective to spread said segments, and links pivoted to said segments and member with a lost-motion connection whereby they are effective to spread said segments further after initial movement thereof.

5. In a coil holder, a rotatable mandrel, coil-engaging segments movable radially in the mandrel, a wedging member movable axially in the mandrel and effective to spread said segments, and links pivoted to said segments and having a pin and slot connection with said member whereby said links become operative to further spread said segments only after initial movement thereof by said member.

6. A coil holder comprising a mandrel, a journal portion extending from one end of the mandrel and rotatable on spaced bearings, segments spaced circumferentially of the mandrel and movable radially thereof, an expander movable axially of the mandrel and having wedging surfaces cooperating with similar surfaces on said segments, and links pivoted to said segments and mandrel with a lost-motion connection whereby they are effective after initial movement of said segments by said surfaces to cause further spreading thereof.

7. In a coil holder, a rotatable mandrel, coil-engaging segments movable radially in the mandrel, a wedging member movable axially in the mandrel and effective to spread said segments, links pivoted to said segments and member with a lost-motion connection whereby they are effective to spread said segments further after initial movement thereof, a shaft extending from said member coaxially of the mandrel and means for reciprocating said shaft.

8. A coil holder comprising a mandrel, a journal portion extending from one end of the mandrel and rotatable on spaced bearings, segments spaced circumferentially of the mandrel and movable radially thereof, an expander movable axially of the mandrel and having wedging surfaces cooperating with similar surfaces on said segments, links pivoted to said segments and mandrel with a lost-motion connection whereby they are effective after initial movement of said segments by said surfaces to cause further spreading thereof, a shaft extending from the expander through said journal portion, and means for reciprocating said shaft.

9. A coil holder comprising a mandrel, a journal portion extending from one end of the mandrel and rotatable on spaced bearings, segments

spaced circumferentially of the mandrel and movable radially thereof, an expander movable axially of the mandrel and having wedging surfaces cooperating with similar surfaces on said segments, links pivoted to said segments and expander and means for driving said journal portion.

10. A coil holder comprising a mandrel, a journal portion extending from one end of the mandrel and rotatable on spaced bearings, segments spaced circumferentially of the mandrel and movable radially thereof, an expander movable axially of the mandrel and having wedging surfaces cooperating with similar surfaces on said segments, links pivoted to said segments and mandrel, a shaft extending from said expander through said journal portion, power means for shifting said shaft axially, and means for driving said journal portion.

11. A coil holder comprising a horizontal member having an overhanging end, means supporting said member for rotation, segmental coil-engaging shoes movable radially of said member, a wedging member movable longitudinally of said first mentioned member, said wedging member having surfaces adapted to force said shoes outwardly on longitudinal movement of the wedging member relative to the first mentioned member, and links pivoted to said wedging member and shoes with a lost-motion connection whereby they are effective to cause further outward movement of the shoes on continuance of such movement of said wedging member.

12. A coil holder comprising a horizontal member having an overhanging end, means supporting said member for rotation, segmental coil-engaging shoes movable radially of said member, a wedging member movable longitudinally of said first mentioned member, said wedging member having surfaces adapted to force said shoes outwardly on longitudinal movement of the wedging member relative to the first mentioned member, and links pivoted to said wedging member and shoes adapted to cause further outward movement of the shoes on continuance of such movement of said wedging member, the pivoted connection between the links and one of said members including slots.

13. In a coil holder, a mandrel rotatably supported as a cantilever, with one end free to receive a coil, segments movable radially of the mandrel to engage a coil interiorly, a shaft slideable axially of said mandrel, means actuated by movement of said shaft for effecting movement of said segments, and bearings in said mandrel adjacent both ends of said segments, supporting said shaft for axial sliding and serving to transmit to the mandrel directly the bending moment applied to the shaft by the weight of a coil carried on said segments.
